DOUBLE FLANGED BUTTON

Harold J. Reiter, Chicago, Ill.

Application January 3, 1935, Serial No. 202

5 Claims. (Cl. 24—109)

This invention relates to metal buttons and particularly, to the type having a cap or flange at each end thereof.

Such buttons are frequently used in connection with rubber bathing caps to attach the chin strap to the cap. The flange of the button is forced through a slit in the cap and another slit or button hole in the strap. Due to the resistance and friction of the metal upon the rubber, it is 5 more or less difficult to force the flange, head or cap of the button through its button hole, which is usually quite tight. Furthermore, if the button is tightly held in the slit or button hole of the cap, the flange may chafe the face of the user.

10 My invention therefore contemplates the provision of a double flanged metal button wherein the caps of the flanges are so mounted as to permit the flange to be inserted easily through the slit or button hole of the cap or strap by a 15 rolling action and wherein the caps of the flanges and particularly the one adjacent the face are also free to turn or rotate and thereby to prevent chafing of the face of the wearer.

The various objects of my invention will be 20 clear from the description which follows and from the drawing, in which,

Fig. 1 is a perspective view of a bathing cap to which my invention has been applied.

Fig. 2 is a similar view on an enlarged scale 25 of a portion of a strap showing how the button flange may be rolled through the tight cap slit or button hole.

Fig. 3 is a vertical section of my improved button in its operative position connecting two parts 30 of an article.

Fig. 4 is a top view and partial horizontal section of the same.

It will be understood that my improved button 35 may be applied to a variety of different articles but it is preferably used in connection with rubber articles such as bathing caps or the like. In such caps as 10, there is customarily provided a strap as 11 also made of rubber or similar material and provided with a button slit or button hole 12. The cap is also provided with a slit or button hole 13 which may be smaller than the slit 12, if desired, since the button is seldom, if ever, removed therefrom.

In that practical embodiment of my invention 50 which I have illustrated by way of example, my improved button comprises the one-piece eyelet 14 provided with an integral flange 15. A second similar one-piece eyelet having a flange 16 and a tubular portion 17 of smaller diameter than the tubular portion of the eyelet 14 is inserted into

said eyelet 14 in relatively reverse position (Fig. 3). The tubular portion 17 of the inner eyelet is made longer than the corresponding portion of the outer eyelet 14 to provide sufficient material to permit the flanging of the open end of the tubular portion on to the outermost face of the base flange 15 as at 18 and thereby to hold the eyelets securely together. Similarly, the open end of the tubular portion of the eyelet 14 is similarly flanged against the innermost face of the 5 base flange 16 of the inner eyelet as at 19. There is thus provided a shank 20 on the eyelet adapted to pass through the button holes 12 and 13.

In order to finish the button and to provide the rotating or rolling action hereinbefore mentioned, the flanges 15 and 16 of the respective outer and inner eyelets are suitably capped. Toward this end, the cap 21 of sheet material in the form of a disc is arranged about the flange 15. The rim of the cap 21 comprises a circular 15 bend as 22 preferably subtending an angle of more than 180° and bent inwardly about the peripheral edge 23 of the flange 15. The bend 22 terminates in a peripheral portion 24 bent toward the flange 15 and terminating in an edge 25 20 close to the adjacent face of the flange 15 but out of contact therewith. It will be understood that the cap 21 is fitted about the flange 15 sufficiently closely to prevent undue relative movement or rattling thereof but with sufficient 30 looseness to permit said cap to turn freely about the flange 15 and relatively to the remainder of the button including the shank 20.

To aid in securing a proper fit of the cap 21 about the flange 15, said cap is provided preferably with a central conical depression as 26 entering the interior of the tubular portion 17 of the inner eyelet and arranged closely to but preferably out of contact with the spread, turned, or flanged portion 18.

The cap 27 for the flange 16 of the inner eyelet is formed similarly to the cap 21, being provided with the conical recess 28, the bend 29 and the peripheral portion 30. It will be understood that the extremity 31 of the portion 30 is preferably 40 out of contact but arranged closely to the flange 16 so as to permit turning, rolling or rotation of the cap 27 about said flange 16.

In operation, the cap 27 is forced through the 50 slit or button hole 13 of the cap or other article in the customary manner as by forcing part of the bend 29 therethrough and gradually forcing the remainder of the cap through said slit, it being understood that the button may remain 55 in place attached to the cap 10 or other article

and that it is the strap 11 which is more frequently removed from and attached to the cap part 21 of the button. The slit 12 is therefore made preferably longer than the slit 13. To 5 insert the head or cap 21 of the button through said slit 12, the parts are arranged in the position indicated in Fig. 2 and the cap 21 is simultaneously rotated or rolled about the shank 20 of the button, thereby permitting said cap to roll 10 through the slot with a minimum of friction and easily.

The strap 11 may therefore be rapidly and easily attached to the button cap 21 and by reason of the inherent resiliency of the material 15 of the strap and the consequent contraction of the edges of said slit about the shank, is securely held in place. Since the cap 27 at the other end of the button is also rotatable about the shank 20 of the button, it will be obvious that any 20 pressure on the button cap 27 will not cause chafing of the skin of the wearer or relative movement of the cap on the face, since the cap 27 will rotate under such pressure and accommodate itself to the various positions of the cap 25 on the face.

It will be seen that I have provided a simple though inexpensive and efficient button to which a strap may be rapidly and easily attached and which prevents chafing of the face. It will further be seen that I have provided a simple button 30 designed to meet the requirements of practical use.

While I have shown and described certain specific embodiments of my invention, it will be understood that I do not desire to limit myself thereto but intend to claim my invention as broadly as may be permitted by the state of the prior art and the scope of the appended claims. 35

I claim:

- 40 1. In a double-flanged button, a tubular shank, and a sheet metal cap overhanging each end of the shank and rotatable thereon.
2. In a double-flanged button, a tubular shank,

and a sheet metal cap overhanging each end of the shank and rotatable thereon, said caps each having a central portion therein bent toward the other cap and entering the shank.

3. A button comprising a pair of telescoped eyelet members each provided with a peripheral flange, the flanges of said members being arranged in opposed relation at opposite extremities of the button, and a cap loosely mounted on each of the flanges and rotatable thereon. 5

4. A double-flanged button comprising an eyelet having a tubular shank portion open at both ends and having an integral flange outstanding from one of the open ends of said portion, a second eyelet having a tubular shank portion open at both ends and shorter than and inserted through the shank portion of the first-mentioned eyelet and having an integral flange outstanding from one of the open ends of said shank portion, an outwardly spread part on the unflanged end of the shank portion of the first-mentioned eyelet, said spread part engaging the outermost face of the flange of the second eyelet, an outwardly spread part on the unflanged end of the shank portion of the second eyelet engaging the innermost face of the flange of the first-mentioned eyelet, and a cap arranged about each of said flanges, said cap having a rim bent loosely around the peripheral portion of its corresponding flange and thereby being rotatable thereon. 10 15 20 25

5. In a double flanged button, a pair of eyelets each having a hollow shank and a flange at one end of the shank, the shank of one eyelet being inserted through the shank of the other eyelet and flanged on to the flange of said other eyelet, and a sheet metal cap enclosing the flange of each of the eyelets, each of the caps having a rim bent over the edge of the flange and terminating in an edge out of contact with said flange whereby the caps are freely rotatable on the respective flanges, each of said caps having a central conical indent therein extending into the shank of the inner eyelet. 30 35 40

HAROLD J. REITER.
